UNITED STATES PATENT OFFICE.

JOHN L. WALSH AND HERBERT H. REIBER, OF PHILADELPHIA, PENNSYLVANIA.

WRENCH.

1,366,224.

Specification of Letters Patent. Patented Jan. 18, 1921.

Application filed June 14, 1920. Serial No. 388,962.

To all whom it may concern:

Be it known that we, JOHN L. WALSH and HERBERT H. REIBER, citizens of the United States, residing at Philadelphia, county of 5 Philadelphia, and State of Pennsylvania, have invented certain new and useful Improvements in Wrenches, of which the following is a specification.

Hoppers on freight cars, such for example 10 as the inclined hoppers on the bottoms of coal cars, have their hinged bottom plates locked by means of cables or chains which are wound on rotatably mounted shafts. These shafts have angular ends which project slightly beyond the side of the car and have ratchet wheels secured thereon which are locked against rotation by pawls which are mounted on the side of the car. Theoretically if a wrench is applied to one of 15 said shafts and turned to permit release of the pawl, the bottom plate should immediately start to swing downward to release and allow the discharge of the load. Due to a number of causes, such for example as 20 the jamming or freezing of the material, the bottom plates do not fall until after the shafts have been turned to slacken a considerable length of the chain or cable and then the bottom plates suddenly fall and 25 the result is that the wrench is thrown from the hand of the workman or breaks his arm or otherwise seriously injures him.

One object of our invention is to provide 30 an improved car hopper wrench which will facilitate the opening of car hoppers and at the same time will be so constructed as to prevent injury to the workman while attempting to open the hoppers.

Another object is to so construct our improved wrench that it will permit of a good 35 leverage so that the workman can conveniently operate the same irrespective of the style or type of car having the hopper thereon.

Another object is to make our improved wrench of a simple and durable construction and so that it can be readily manipulated.

These objects, and other advantageous 50 ends which will be described hereinafter, we attain in the following manner, reference being had to the accompanying drawings in which—

Figure 1 is a side elevation of our improved wrench; a portion of the hand-lever being 55 broken away; said view showing various po-

sitions which the free swinging outer hooked jaw can attain, and

Fig. 2 is an edge view of Fig. 1.

Referring to the drawing, 3 represents a hand-lever which may be made of strong metal which has a head 4; said head at its free end being bifurcated to provide a recess 5 between the furcations 6 thereof; said furcations being arranged substantially parallel as shown in Fig. 1. A pivot pin 7 extends through the furcations 6 and transversely across the recess 5; said recess extending entirely through the head 4. It will be noted that as shown in Fig. 2 the end surfaces 8 will abut the surface 11 of the head 70 jaw 9 when the hand-lever is swung into the positions shown at *x* and *y* in Fig. 2. The upper or outer surface 12 of the head jaw 9 includes transversely extending ribbed teeth 13; said teeth being arranged in an arc 75 which leads upwardly from the portion 14 adjacent one of the furcations 6. The portion 15 opposite the part 14 has a notch 16; the inner side thereof being substantially parallel and the innermost surface 17 as 80 shown in dotted lines in Fig. 1 extends at a slant from the surface 11 to the surface 12 so that certain of the uppermost teeth 13 are discontinued in their width by the notch 16 as clearly shown in Fig. 2. A pivot pin 17 85 extends through the part 15 across the notch 16 and a free swinging outer hooked jaw 18 has an arm 19 which fits within the notch 16 and has a pivot hole through which the pivot pin 17 extends. Thus the outer free 90 jaw 18 is free to swing in a plane substantially at right angles to the plane in which the jaw 19 swings. The hooked jaw 8 has a row of transversely ribbed teeth 20 on the under surface of its hooked end 21; said 95 teeth 20 being opposed to the teeth 13 of the head jaw 9 so that the wrench can be used to present the opposed teeth 13 and 20 to the angular portion of a hopper shaft to cause the rotation of the latter.

In the use of our improved wrench it is immaterial from which side of the shaft the wrench is applied since the hand-lever can be swung in either direction so as to present a good leverage for the workman at 100 a position away from any projections such as ribs, bolts or the like on the side of the car. During the use of the wrench if the bottom plates should not immediately open, such for example as under the conditions 110

mentioned in the foregoing objects of the invention, and should suddenly fall after the operating shaft has been slackened the resulting action, instead of throwing the wrench to cause injury to the workman, will merely throw the free outer hooked jaw 18 into an open and inoperative position; thereby releasing the wrench from the shaft. In actual practice it has been found 10 that when the bottom plate suddenly falls the action of the angular portion of the shaft will merely throw or swing the jaw 18 on the pivot pin 17 and the hand-lever will remain in the hands of the workman without 15 out in any way injuring him or causing discomfort.

It will be noted that the teeth 20 are shaped so that one side of the intermediate teeth are longer and at a greater slant than 20 the opposite sides. This shaping of the teeth 20 provides an immediate release from the angular portion of the shaft and at the same time good biting portions are provided for engagement with the shaft during the 25 rotation of the same.

While we have described our invention as taking a particular form, it will be understood that the various parts of our invention may be changed without departing 30 from the spirit thereof, and hence we do not

limit ourselves to the precise construction set forth, but consider that we are at liberty to make such changes and alterations as fairly come within the scope of the appended claim.

35

Having thus described our invention, what we claim as new and desire to secure by Letters Patent is:—

A hopper bottom releasing wrench of the character described including a head jaw; an elongated hand lever pivotally connected at one end to the head jaw and adapted to swing laterally with respect to said jaw, said jaw having an edge surface opposed to said end of the hand lever and including a 40 row of teeth arranged in a convex arc; a second jaw; and a pivot pin pivotally connecting said jaws, said second jaw having a row of teeth adapted to swing on said pivot pin as an axis in an arc toward and from 45 said teeth of the head jaw; substantially as described.

50

In testimony whereof we have signed our names to this specification in the presence of two subscribing witnesses.
